TONGUE AND NECK YOKE COUPLINGS

Filed March 26, 1926

Patented Dec. 18, 1928.

1,695,731

UNITED STATES PATENT OFFICE.

ROBERT HAYDEN HOLLIS, OF KAMLOOPS, BRITISH COLUMBIA, CANADA.

TONGUE AND NECK-YOKE COUPLING.

Application filed March 26, 1926. Serial No. 97,690.

The invention relates to improvements in tongue and neck yoke couplings and has for its object the provision of a comparatively simple, inexpensive device which will securely couple the neck yoke to a vehicle tongue or pole, one whereby free movement of the yoke relative to the pole will be permitted and one in which the neck yoke may be readily connected with or disconnected from the pole and its accidental disconnection prevented.

A further object is to construct the device so that foreign matter lodging therein can be readily cleared out.

15 A further object is the provision of a device which will permit of the using of the present type of neck yoke having a pole receiving ring when such is desired.

20 With the above more important objects in view the invention consists essentially in the arrangement and construction of parts hereinafter more particularly described, reference being had to the accompanying drawing, in which:—

25 Fig. 1 is a side view of the device showing it in normal position and connecting the neck yoke to the pole.

Fig. 2 is a plan view of the parts appearing in Figure 1.

30 Fig. 3 is a vertical longitudinal section through the centre of the pole and neck yoke showing the device in the position occupied when the draft animals are holding back.

35 Fig. 4 is a view similar to Figure 3 showing the device in the position it will occupy if the harness tugs break.

Fig. 5 is a rear view of the socket-like casting.

40 In the drawing like characters of reference indicate corresponding parts in the several figures.

It is a well known fact that the type of neck yoke now most commonly in use and having a ring for receiving the pole is unsafe and dangerous in use for the reason that in case the draft animals take sudden fright or lunge forward, the ring is liable to and often does slip off the end of the pole allowing the front end of the latter to fall to the ground causing possibly the wrecking of the vehicle or serious injury to the occupants thereof. The device which I have provided avoids any such possibility and whilst so avoiding it is constructed so that it can be coupled or uncoupled easily and quickly and can be manufactured in a dura-

ble manner and at comparatively small cost.

The vehicle pole or tongue 1 is of the conventional type as is also the neck yoke 2. The neck yoke is provided centrally in the present instance with top and bottom bearing plates 3 and 4 which are attached to the neck yoke by eye bolts 5 and 6, the eyes being at the under side of the yoke. Usually these eyes support a ring adapted to receive the forward end of the pole but in my case, 60 they carry a special socket-like member 7.

The member 7 is provided at the upper end with eyes 8 and 9 which are connected to the eyes of the eye bolts 5 and 6 by rings 5' and 6' whereby the said member 7 is 70 swivelly swung in a pendant position from the center of the neck yoke. The member 7 is cast or otherwise made to provide a vertically disposed pocket or socket 10 having 75 the upper end 11 open and inclined and the lower end thereof semi-spherical and provided with a discharge opening 12. The rear part of the said member is provided also with a vertical slot 13, opening into the 80 pocket, the edges of the slot being rounded.

The forward end of the tongue thereof abuts against a head 14 which entirely covers the end of the tongue to prevent reins or straps from catching on the tongue at this 85 point and the head is provided with two rearwardly extending arms 15 and 16 which are fastened to the tongue by bolts 17 passing therethrough. The head is formed to present also a horizontally extending neck 90 18 which terminates in a ball end 19. The ball is adapted to enter the socket through the opening in the upper end thereof and is adapted to pass down into the spherical end of the socket, the neck in the meantime sliding down within the slot 13. Under normal 95 pulling conditions of the draft animals, the parts appear approximately in the position shown in Figure 1 where it will be observed that the forward end of the tongue is supported from the neck yoke in a substantially horizontal position by the ball resting in the lower end of the pocket.

The neck and the slot are so designed that a free swivelling movement of the ball in 105 the socket is permitted and further the parts are so arranged that when the draft animals are holding back, the neck yoke can take a position above the tongue without there being any jamming action of the socket body 110 against the head or forward end of the tongue.

If reference be made to Figure 3 wherein the device is shown in the latter position, it will be seen that the design of the socket is such that it does not catch in any way on the pole or pole fittings but swings freely back towards the pole and at this time any free movement required in the neck yoke will be accommodated by the ordinary connections which fasten the ends of the neck yoke to the animals. It will be further noted that in the latter position of the neck yoke, the tongue cannot escape from the socket as it is being forced into the closed end of the socket. Should the draft animals suddenly lunge forward or the tugs break, the position of the parts will be such as shown in Figure 4 and here it will be noted that the ball is retained within the socket and cannot escape therefrom.

If at any time it is desired to detach the neck yoke from the tongue or pole, this is done very readily by raising the ball to pass it out the upper end of the socket. As the open end of the socket is inclined, it is a very easy matter to place the ball in the socket when desired as it will be apparent that when the ball has been brought to a position where it strikes the upper or most elevated part of the member 7, it can be then readily dropped into the socket and the inclined edges at 11 will direct the neck into the slot.

Whilst I have shown the device provided with two eyes, one could be used where the neck yoke fittings only provide a single eye

bolt. The hole 12 is provided to permit snow and dirt to escape from the pocket. In Figure 1 of the drawing, I have shown in dotted outline the customary strap 20 fastened to the under side of the tongue by the bolt 17 and presenting the usual knee or shoulder 21 against which the customarily used neck yoke ring engages. This strap can obviously be mounted on the tongue when desired, that is, in instances where it may be necessary to use the ordinary neck yoke carrying the customary tongue receiving ring.

What I claim as my invention is:

A tongue and neck yoke coupling comprising a socket-like member open at the upper end, the upper edge of said member being inclined downwardly from front to rear, the rear side thereof being provided with a vertical slot and the front side thereof being fitted at the upper end with spaced eyes, rings passing through the eyes, eye bolts passing through the rings and connecting the socket member centrally to the under side of the neck yoke and a head secured to the forward end of the tongue and presenting a horizontally extending neck terminating in a ball end, the ball being adapted to slidably enter the socket through the upper end thereof and the neck to pass downwardly through the slot.

Signed at Kamloops, B. C. this 21st day of August 1925.

ROBERT HAYDEN HOLLIS.
